[57] CLAIM

The ornamental design for a magnetic support supporting a notepad and for mounting a business card, as shown and described.

DESCRIPTION

FIG. 1 is a top, front and left side perspective view of a magnetic support supporting a notepad and for mounting a business card showing my new design;

FIG. 2 is a front elevational view thereof;

FIG. 3 is a left side elevational view thereof and a mirror image of a right side elevational view thereof;

FIG. 4 is a rear elevational view thereof;

FIG. 5 is a top plan view thereof; and,

FIG. 6 is a bottom plan view thereof.

The broken line depiction of the area for the mounting of business cards in FIGS. 1 and 2 has been shown for illustrative purposes only and forms no part of the claimed design.
